UNITED STATES PATENT OFFICE.

LEWIS A. FOOTE, OF CHICAGO, ILLINOIS, ASSIGNOR TO CHICAGO CAR SEAL & MANUFACTURING COMPANY, OF CHICAGO, ILLINOIS, A CORPORATION OF ILLINOIS.

SEAL.

No. 819,347.

Specification of Letters Patent.

Patented May 1, 1906.

Application filed August 7, 1905. Serial No. 273,020.

To all whom it may concern:

Be it known that I, LEWIS A. FOOTE, a citizen of the United States, residing at Chicago, in the county of Cook and State of Illinois, have invented a new and useful Improvement in Seals, of which the following is a specification.

My invention relates particularly to car-seals; and my primary object is to provide, 10 in connection with a hasp-pin of a car-door, a simple and inexpensive seal possessing the highest degree of security.

The invention is illustrated in its preferred embodiment in the accompanying drawings, 15 in which—

Figure 1 represents a broken perspective view of the staple and hasp of a car-door with my improved seal applied thereto; Fig. 2, an enlarged horizontal sectional view taken as 20 indicated at line 2 of Fig. 1; Fig. 3, a broken perspective view of two sheet-metal members adapted to interlock within the transverse slot or key-opening of the pin, and Fig. 4 a broken perspective reverse side view of one 25 of the members shown in Fig. 3.

In the construction shown, A represents a hasp; B, a staple received thereby; C, a pin securing the hasp upon the staple and provided with a rectangular transverse key- 30 opening or slot c; and D D' two sheet-metal members provided, respectively, with male and female extensions or tongues interlockingly connected within the slot c.

The member D comprises a body portion 35 d, of rectangular form, and a male tongue d', having a portion d² in the plane of the body portion and a portion d³ at one side of the portion d² and equipped with a lateral projection d⁴. The whole member D is integrally 40 formed by bending a rectangular extension of reduced cross-section upon itself to form the parts of the tongue. The base of the tongue is flanked above and below by shoulders d⁵ and at the sides by the lateral projection d⁴ and a boss d⁶, struck transversely in 45 the body, as shown. Thus shoulders are provided on all four sides at the base of the tongue, which prevent the insertion of an implement with a view to tampering with the 50 lock of the seal. The tongue is provided at different points in its length with transverse perforations or prong-receiving sockets d⁷ d⁸.

The member D' comprises a body d⁹, of

rectangular form, and a female tongue or open-ended hollow extension d¹⁰, which fits 55 accurately within the slot c of the pin and accurately receives the tongue d' of the member D. The hollow tongue d¹⁰ is provided internally at its two lateral sides and at different points in its length with rearwardly-pointing spring-prongs d¹¹ d¹², which engage, 60 respectively, the perforations d⁷ d⁸ of the tongue d'. The whole member D' is integrally formed of sheet metal by cutting and bending the metal to form the top and bottom portions d¹³ d¹⁴ and the side portion d¹⁵ of the tongue, the longitudinal edges of the metal meeting at the line d¹⁶. Thus shoulders d¹⁷ are provided above and below the tongue, which abut against the pin when the 70 seal parts are joined. As indicated, the tongues are just of sufficient length to extend through the pin. One or both of the members D D' are adapted to receive any desired marking. Thus the member D is shown 75 marked with the characters "X. Ry. Co., No. 1001." Usually the seals are supplied during manufacture with the name of the user and are consecutively numbered.

The manner of use is evident. After the 80 hasp has been received by the pin the tongue of the member D' is entered in the key-opening of the pin from one direction, and the tongue of the member D is entered in the tongue of the member D' from the opposite 85 direction, the catches d¹¹ d¹² yielding to permit this action and then springing into the sockets d⁷ d⁸ and interlockingly connecting said members. In this condition the shoulders at the bases of the tongues abut against 90 the sides of the pin, thus preventing the device from being tampered with, even should there be a slight inaccuracy in the fit of the parts. To enable removal, the body of the member D' may be broken from the tongue, 95 thus enabling withdrawal of the member D, and with it the tongue of the member D'.

Changes in details of construction are contemplated. Hence no undue limitation should be understood from the foregoing detailed description.

What I regard as new, and desire to secure by Letters Patent, is—

1. The combination with a hasp-pin provided with a transverse key-channel, of a 105 sheet-metal member comprising a body por-

tion and a hollow open-ended tongue formed integrally therewith, the metal being cut and bent into box form to form said tongue, and a sheet-metal member comprising a body portion and a projecting portion bent upon itself to form a tongue, the key-channel receiving said first-named tongue and said first-named tongue receiving said second-named tongue, said tongues being provided with interlocking 10 means preventing separation, for the purpose set forth.

2. The combination with a hasp-pin provided with a transverse key-channel, of a sheet-metal member equipped with a hollow 15 tongue having struck-in spring-catches, and a sheet-metal member equipped with a tongue provided with sockets receiving said spring-catches, said tongues being telescoped together within and filling said key-channel for 20 the purpose set forth.

3. The combination with a hasp-pin having a transverse key-channel, of a sheet-metal member having the metal cut transversely at its lateral edges and bent, forming a hollow 25 open-ended tongue, the bent portion of the metal lying at one side of the body of the member, and a sheet-metal member having an extension of reduced cross-section bent upon itself forming a tongue, the extremity 30 of said extension being bent laterally, forming a shoulder at the base of the tongue, said tongues being in telescopic connection within and filling the key-channel and having interlocking connection preventing separation, 35 for the purpose set forth.

4. A self-locking seal adapted for use in connection with a hasp-pin, comprising a sheet-metal member having a projecting hollow tongue and provided with a struck-in 40 spring-catch, and a sheet-metal member having a projecting tongue adapted to fit within said first-named tongue and provided with a socket for said catch.

5. A seal for use in connection with a hasp-pin comprising a sheet-metal member having a hollow tongue, the metal being cut transversely at its lateral edges and bent into box form to form said tongue, and a sheet-metal member having an extension of reduced cross-section bent upon itself and forming a tongue 45 adapted to fit accurately within said first-named tongue, one of said tongues having its metal struck in to form a spring-catch, and the other tongue having a socket for receiving said catch.

6. A self-locking seal for use in connection with hasp-pins, comprising a sheet-metal member having the metal cut transversely at its lateral edges and bent to one side of the body portion forming a hollow open-ended tongue, the metal being struck in at the sides of said tongue at different places in the length of the tongue, and a sheet-metal member having a tongue fitting within said first-named tongue and provided at different points in its 50 length with sockets receiving said catches.

LEWIS A. FOOTE.

In presence of—

L. HEISLAR,
J. H. LANDES.
